CABLE JOINT AND METHOD AND MEANS
FOR FORMING SAME

Ernest Williams, Jackson Heights, and Constantine P. Xenis, Little Neck, N. Y., assignors to Consolidated Edison Company of New York, Inc., New York, N. Y., a corporation of New York

Application November 15, 1939, Serial No. 304,587

11 Claims. (Cl. 113—112)

This invention relates to improved cable joints and novel methods and means for forming same, and is particularly applicable to joints in electric power cables and electrical communication wire cables of the types enclosed in lead or other metallic sheaths.

This application is directed to various alternative embodiments and improvements of the inventions of our copending application Ser. No. 304,586 filed on even date herewith, entitled "Cable joints and methods of forming same."

Joint constructions for lead covered cables and the like are customarily covered, protected and strengthened by a lead or other metallic sleeve enclosing the spliced portions of such cables. For many years it has been the practice to effect a seal between the ends of such sleeves and the cable sheaths by "beating in" the ends of the sleeve to an extent such that the peripheral edges contact with the cable sheath, and then the region at the end of the sleeve is "wiped" by hand with solder chilled to plasticity. Such wiping operation has to be performed by skilled workmen who have gone through a considerable period of training if the occurrence of leaky or porous "wipes" is to be avoided, even with cables of relatively small size. However, with the use of cables of larger size requiring larger wipes, and particularly with complicated joints or where two or more cables enter the sleeve at one end of the joint, there is great difficulty in securing reliable wipes and only a small portion of the more skillful and experienced workmen trained in this art are able to accomplish the task, and sometimes the operations fail and have to be repeated before successfully completed.

In performing the wiping operations, solder is melted in a pot, and then poured by the use of a hand ladle on to the area of the desired wipe. A portion of the solder thus poured adheres in a plastic condition to the cable sheath or the sleeve, provided the poured solder is at the proper temperature, and the remainder is received in a wiping pad held in the hand of the operative just beneath the cable. This pouring operation is repeated again and again, while the pad with solder thereon must be skillfully wiped over the area of the desired seal until a sufficient mass of plastic solder is built up to form a poultice-like seal between the sleeve and the cable sheath. The difficulties with this method arise from various causes. If the solder is too hot or if too much solder is poured on to one area, either the sleeve or cable sheath will be "burned" quickly through, that is, a hole will be melted through,

ruining the joint or the cable. Also, particularly with the larger joints, if the plastic mass of solder as it accumulates on the joint is slightly too soft, it may collapse and fall away, requiring the operative to start anew. Again, if the mass of solder solidifies before a smooth continuous wipe has been formed, crevices and irregularities will occur impairing the strength and durability of the seal or affording areas prone to leakage. While such an imperfect joint sometimes might be corrected by applying a blow torch, the use of open flames in underground manholes or passages offers a hazard from gas explosions and is therefore generally prohibited. There is a relatively narrow temperature range of plasticity required of the solder to permit sufficient workability and this necessitates skillful timing of the operations in forming the wipe. Solder with 40% tin and 60% lead as normally used for this type of work, has a plastic range of approximately 55° C., or from about 238° C. down to 183° C., the latter temperature being the solidifying point of the eutectic mixture (63% tin and 37% lead). In the wiping process as the solder is cooled to a plastic workability, there is a solidification of lead particles or crystals at temperatures above 183° C., the solidifying point of the eutectic mixture. Yet due to the fact that the eutectic mixture remains liquid down to 183° C., it tends to run out of or to the bottom of the mass being formed, leaving the wipe coarse or porous toward the top. This effect is particularly pronounced in larger wipes. For example, it has been found very difficult to secure reliable non-porous wipes on the larger cables without resorting to the hazardous glazing process.

Further disadvantages of the customary wiping process reside in the following facts. The necessity of maintaining a pot of the molten metal at hand, particularly in confined spaces during underground work, is a dangerous hazard, as is also the ladling and pouring of such metal. The operatives are frequently seriously burned. The "beating in" of the sleeve for complicated joints requires much time, and skilled work. Often supplemental end parts must be formed and fitted, on the job, between a plurality of cables. The wiping operation for each large joint requires the services of the skilled operative for several hours even if the operations do not have to be repeated. And the quality and useful life of the resulting joint often depend largely upon chance or the skill of the workman.

While efforts have been made for years to provide some method of avoiding the above difficult-

ties and hazards, so far as we are aware such efforts have not, prior to our inventions, produced any substitute method or construction which has gone into any substantial practical use in replacement of the manual wiping operation.

The objects of this invention include the provision of improved joint constructions and methods, and novel molding apparatus for forming same which will avoid in practice, the above-mentioned difficulties and make possible the formation of more dependable and uniformly satisfactory seals, with a substantial saving of time and without requiring the operative to have any high degree of skill or long experience. Various features of the invention are also applicable to the problem of sealing metallic sheathed cables within terminal bushings or the like, for example at points where the cables enter a transformer or other piece of electrical equipment.

Various further and more specific objects, features and advantages will clearly appear from the detailed description given below taken in connection with the accompanying drawings which form a part of this specification and illustrate merely by way of example preferred forms of the invention. The invention consists in such novel methods and method steps, features, arrangements and combinations of parts as may be shown and described in connection with the constructions herein disclosed.

In the drawings:

Fig. 1 illustrates a plurality of cable ends to be spliced, and also showing a desirable preliminary arrangement of the parts to be used in forming a cable joint according to the invention.

Fig. 2 is a view similar to Fig. 1 but illustrating the next steps in forming the joint, after the cable ends have been spliced and electrically insulated.

Fig. 3 illustrates the positions of various parts of the cable joint during a succeeding step.

Fig. 4 is an end view showing the parts of a molding means which may, for example, be applied to the cables at the left-hand end of the joint of Fig. 3.

Fig. 5 is a view similar to Fig. 3 but showing molding means applied to both ends of the joint and filled with solder for sealing the ends of the joint.

Fig. 6 is a side view of a completed cable joint showing the manner in which the mold parts may be removed.

Figs. 7 and 8 respectively are perspective views of the finished seals at the left and right-hand ends of the cable joint of Fig. 6.

Fig. 9 is a perspective view of an alternative form of mold.

Fig. 10 is an elevational view of the latter mold.

Fig. 11 is a sectional view taken substantially along the line 11-11 of Fig. 10.

Figs. 12 and 13 illustrate certain details of the mold of Fig. 10.

Fig. 14 is a diagram of the electrical heater connections for a mold, such for example as of Fig. 10.

Fig. 15 is an end view of a barrier member which may be used in forming a joint as of Fig. 5, for example.

Fig. 16 is a sectional view taken substantially along the line 16-16 of Fig. 15.

Figs. 17 and 18 respectively are face and top views showing further details of a mold such as of Fig. 4.

Fig. 19 is a sectional view taken substantially along the line 19-19 of Fig. 17.

Fig. 20 is a view of one of the parts of the mold of Fig. 17 and taken substantially along the line 20-20 of Fig. 17.

Fig. 21 is a face view partly in section of an alternative form of a three-part mold.

Fig. 22 is a sectional view taken substantially along the line 22-22 of Fig. 21 showing the mold as applied in use to a joint construction.

Fig. 23 is a top view of the mold of Fig. 21.

Fig. 24 is a perspective view of a finished seal as made with a mold as of Fig. 21, for example.

Fig. 25 is a face view of another barrier member similar to that of Fig. 15 but adapted for receiving and supporting three cables, and

Fig. 26 is a sectional view taken substantially along the line 26-26 of Fig. 25.

Referring now to Figs. 1 to 3: a plurality of cable ends, as at 30, 31, 32, 33, are shown coming into one end of a proposed joint, and a single cable end 34 is shown for coming into the other end. While the particular joint here shown is a so-called "one-way x four-way joint," it will be understood that the invention is equally applicable to either simple joints of a single cable end, to another cable end, or to joints having a plurality of metal-sheathed cables of various different sizes and numbers coming into each end of the joint. The cables may be high or low voltage power cables with or without fluid pressures therein, or may be for telephone, telegraph or other communication purposes.

The cable ends may have threaded thereon gaskets (as at 35, 36, 37) and metallic barrier members as at 38, 39, the construction and purposes of which will be explained hereinafter. Also a metal sleeve as at 40 for enclosing the finished joint may be placed upon the cable end or ends at one side of the proposed joint. This sleeve is preferably and usually made of lead and is preferably cylindrical although other tubular shapes may be used if desired. Usually also an inner sleeve as at 41 of rigid insulating material is provided.

Suitable insulating electrical joints or splices may be made between the various cable ends as shown at 42 according to well-known methods which need not be here further described. It will be apparent that during the work of making the electrical connections and the insulation thereof at 42, the sleeves 40, 41, as well as the barrier members and gaskets, may be slid back along the cables far enough to afford ready access to the region of the splices. After the splicing and the insulation work are completed, as at 42, the insulation sleeve 41 may be slid over the spliced region to the position shown in Fig. 2. The inner surfaces at the ends, and the ends of the sleeve 40 are scraped clean and coated with stearin or other flux material, and the surfaces of the cable sheaths and barriers at the areas of the desired seals are similarly prepared. Then the barrier member, as at 38, may be placed along the cables at its desired permanent position and tacked with solder to each of the cable sheaths, as at 43, 44. Similarly, the barrier member 39 may be positioned on the cable 34 at its desired permanent position, as indicated in dotted lines (Fig. 2) and tacked in position with solder. Thereupon, the sleeve 40 may be slid into a position such as shown in Fig. 3. The ends of the sleeve 40, if desired, may be slightly flared to enable the sleeve to readily slide over the barriers 38, 39. With the sleeve 40 in place, it may be

tacked with solder as at 45, 46 with respect to the barrier members 38, 39. If necessary, before this is done, the outside surfaces of the ends of the sleeve may be tapped circumferentially in order to cause them to fit tightly around the barrier members 38, 39.

The barrier member 39, as shown in further detail in Figs. 15 and 16, may comprise a disc-like member pressed for example, from sheet lead so as to have an extended peripheral flange, as at 47, designed to extend inwardly of the joint for a considerable distance in contact with the inside walls of the lead sleeve 40, so that when molten solder is applied to the outside surface of the barrier for sealing the joint, any solder which may tend to leak inwardly along the inside surface of the sleeve will have opportunity to become cool and solidify, thereby preventing leakage of solder into the joint past the flange 47. The central area of the barrier member 39 may be apertured as at 48 to permit passage of the cable therethrough. The inner walls of the aperture, as shown (Fig. 16) are preferably shaped with a generally conical flange extending inwardly of the joint, so that the more restricted portion 49 of this flange may closely embrace the cable sheath.

The external dimensions of lead cable sheaths of various specified sizes, often do not accurately conform to the dimensions specified. Consequently in order to insure that the apertured barriers will closely fit the cable sheath, it is necessary to provide for varying the aperture size on each job. This may be readily accomplished with the construction shown, by forming the constricted portion 49 with a diameter small enough to insure a close fit with the smallest cable intended to pass therethrough and for slightly larger cables the constricted portion may be reamed, or expanded somewhat as by a conically shaped tool. The barrier 38 for accommodating a plurality of cables such as at the other end of the joint shown, may be similar to the barrier 39, except as indicated in Figs. 25 and 26, an appropriate number of cable apertures may be provided as at 50, each with conical flanges as at 51 corresponding in construction and purposes to the conical flange in the barrier 39 as above described.

After the barriers 38 and 39 and the sleeve 40 are in position as shown in Fig. 3, packing in the form of lead wool or equivalent means may be inserted as at 52, 53 around each of the cables within the conical flanges at the barrier apertures. The joint is now ready for application of molding means for forming a seal of solder at each end of the joint as shown in Fig. 5.

The molding means at each end of the joint is preferably so shaped as to cast a disc-like wall of solder within each end of the sleeve 40 for integrally sealing the cable sheaths in respect to the inside walls and end edges of the sleeve. Fig. 7 is a perspective view showing the appearance of a preferred form of such a seal for the lefthand end of the joint of Fig. 5. It will be noted that the wall of the solder is largely within the end of the sleeve and therefore is in a position to afford mutual support between the sleeve end edges and the cable sheaths, whereby the same are in effect made into a rigid unitary construction capable of withstanding substantial internal pressures as well as being capable of withstanding machinal shocks and repeated expansion and contraction forces in the cables.

In Fig. 7 it will be further noted that the ca-

bles as they emerge are each surrounded by a collar or flange of solder protruding from the main body of solder 54 as at 55, 56, 57, 58, and integral therewith, and extending along and sealed to the cable sleeves for some distance. Similarly, at the inside surface of the wall of solder 54, flanges as at 59, 60, etc. (Fig. 5) protruding inwardly of the joint will be formed by reason of this shape of the conical flanges at the barrier apertures as above described. Thus although the wall 54 may be made relatively thin, a rigid and extended joint between such wall and each cable sheath is provided, ample to withstand the forces to which the cables may be subjected and sufficiently extensive so that any danger of leakage along the cable sheaths is avoided. Although the wall 54 is substantially flush with the end of the sleeve 40, the mold for forming same may preferably be so shaped as to provide a narrow radially extending peripheral flange of solder as at 61 sufficient to cover and protect the edges of the sleeve and to prevent any danger that the wall may be dislodged inwardly of the joint. The mold for making the wall 54 is preferably so shaped that the gate or sprue will be formed at the location indicated at 62 in Fig. 7. That is, the sprue as shown, extends from the uppermost flange or flanges as at 57, 58 along the outside face of the wall 54 to a point adjacent and just above the upper end edge of the sleeve 40. The gate in this position will insure direct access of solder to the spaces for the uppermost flanges as at 57, 58 even though the final amounts of solder may be introduced after the remainder of the solder in the mold is partially hardened, according to the methods hereinafter explained. While the sprue in this position is not objectionable on the finished joint, it may be readily filed or cut away after completion of the joint if so desired.

Fig. 8 is a perspective view showing the appearance of a preferred form of seal such as for the single cable at the righthand end of the joint of Fig. 5. Features of the construction of Fig. 8 corresponding to those of Fig. 7, are identified by the same reference characters accompanied by prime marks so that the details of construction and purposes of these features in Fig. 8 will be apparent from the above.

An example of a suitable molding means for the seal at the lefthand end of Fig. 5 is illustrated in Fig. 4 with the parts in separated condition. As shown this mold may be made up of three sections as at 63, 64, 65, each extending from side to side of the group of cables and having superimposed lugs as at 66 to 72 inclusive extending to each side. Manually operable screw means as at 73 may be provided at each pair of lugs for clamping the several sections in respect to each other and at the same time serving to clamp the mold parts in respect to the end of the sleeve 40 and to the cable sheaths. It will be noted that each of the mold sections is provided with semi-circular recesses as at 74 for embracing one-half of each cable, and the adjacent mold section in each case being provided with a complementary recess for embracing the other half of each cable. With the mold sections thus extending from side to side and with the clamping means and recesses as shown, the sections may be quickly and conveniently applied and removed from the group of cables and the various cables may be clamped in position with uniform pressure on each and without danger

of excess pressure at any point such as would injure the sheaths.

At the righthand end of the particular joint shown in Fig. 5, molding means as at 15, 16 similar to that of Fig. 4 may be provided, except that the mold 15, 16 need have but two sections to provide for the single cable 34.

Each of the mold sections may be formed with a plurality of cavities as at 17 opening at the outer face of the mold but closed at their inner 10 ends adjacent the inner face of the mold. Each of these cavities is adapted to slidably and removably receive electrical heating elements of the well-known cartridge type. Further details of construction of the molds and modifications 15 thereof will be described hereinafter.

After the molds have been applied to each end of the joint, the gaskets as at 35, 36 and 37 may be forced into annular spaces provided therefor within the cable recesses of the mold sections, 20 as shown in Fig. 5. These gaskets may be formed of cork or other suitable material or composition capable of withstanding the temperature of molten solder and preferably a somewhat yieldable material which may be pressed firmly into place 25 to prevent passage of molten solder outwardly along the surfaces of the cable sheath or along the surfaces of the mold recesses during formation of the seals. A composition of cork and synthetic rubber known in the trade as "Coprene" 30 has been found satisfactory. To prevent leakage of solder at the edges of the sleeve 40, it may sometimes be found desirable to insert packing material such as asbestos wicking or lead floss into an annular space 18 (Fig. 5) provided therefor at the periphery of each mold.

Small quantities of powdered stearin or other suitable flux as required may now be introduced through each of the mold gates as at 19, 19' and then the mold cavities may be filled through these 40 gates with solder in solid state but in such divided form that it may be substantially poured into the molds. Preferably this solder may take the form of rounded pellets or solder shot of somewhat less than $\frac{1}{8}$ " diameter, although in some cases granulated solder may be used if desired. Grade 1, Class 1, solder shot comprised of 50% tin and 50% lead has been found satisfactory. After the solder is thus introduced, the cartridge heaters may be connected and a controlled amount of current may be applied thereto for a limited time, sufficient to quickly melt the solder without overheating, injuring or melting the adjacent lead parts. After the mass of solder becomes molten, it may be allowed to cool while continuing to add through the gates further solder shot or stick solder or the like, sufficient to compensate for shrinkage as the cooling progresses. Preferably the cartridge heaters or the 45 current therein for the lower parts of the molds are removed first so that the lower portions of the solder seals will solidify and shrink while the upper portions are still in molten condition adapted to receive and melt the additional solder for making up the shrinkage. After the seals have become solidified, the mold sections may be removed as indicated in Fig. 6. The central mold section 64 may be slid outwardly along the cables to a point where the slack of the cables will permit its removal. The gaskets as at 35, 37, etc., may 50 preferably be split as indicated in Fig. 6 to facilitate removal and the same may be reused.

If at any subsequent time, it is desired to open the joint, the molds may be put in place again and sufficient heat thereby applied to readily 75

melt down the solder seals without injury to the lead cable sheaths or the lead sleeve, whereupon the sleeves may be slid away and the splice inspected or renewed or readily replaced by a splice with additional or larger cables, for example. Then the joint may be sealed again as before. Or if a larger joint is necessary, the sleeves may be removed for reuse elsewhere and larger sleeves, barriers, etc., may be substituted.

The introduction of the solder in the divided solid forms as above explained, is particularly advantageous in that none of the solder need be made molten until after it is in place within the joint and thus the hazards of maintaining a quantity of molten solder and handling same are eliminated, as are also the difficulties of timing the workman's motions to avoid applying or introducing the molten solder, either too hot or too cool. It may be observed that if molten solder were to be poured into the molds, two sources of heat would be necessary in practice, one for preliminarily melting the solder and the other to heat the molds. Otherwise the molten solder when poured into the mold gates might solidify on striking the cold parts and preclude proper soldering action or preventing filling of the mold. And if two sources of heat were thus used, there would still be danger that the molten solder would enter the molds at too high a temperature and thus melt holes through the lead sleeve, barriers or cable sheaths. However, by introducing the solder in divided solid state, all of the heating may be readily accomplished by electrical means within the molds and under carefully controlled and safe conditions. Also the use of pellets or solder shot appears to offer the further advantage that when the same are being melted within the mold, they will abruptly and intermittently fall or slide over one another and over the surfaces to be soldered, in such a way that the surfaces will be mechanically smeared with the molten solder with a positive action, insuring firm adhesion of the solder to the sleeve, cable sheaths and barriers. That is, the mass of pellets or shot as initially introduced 35 will have a great many interstices or air spaces and the melting solder, in falling into these spaces, will promote the action above referred to.

The upper surface of the sleeve 40 may preferably be provided with a pair of apertures closed by screw plugs as at 80. These screw plugs are preferably removed during the sealing operations so as to relieve any gaseous pressures which might otherwise occur within the joint due to the heating of the ends thereof. And after the seals have been formed at the ends of the joint, suitable insulating liquid may be poured in through 55 one of these openings while the other acts as an air vent.

With the methods and constructions above described, it has been found that operatives, even with little experience, are able to reliably seal complicated and large sized splices in a fraction of the time required for the usual wiping process. At the same time the operatives are not subjected to the hazards of working around or with open masses of molten solder. There is never any necessity of incurring the hazard of using an open flame underground either to glaze the joint or for any other purpose, and there is no danger of spilling the solder onto the workman, and there is no loss from pouring excess solder, as occurs with the wiping method.

Pressure tests made on joints completed in accordance with this invention and under prac-

tical conditions in the field, show that with both high and low voltage cable systems, reliable seals may be produced with a high degree of uniformity, dependability and certainty.

Since the heat is applied electrically while the solder is in place, the amount of heat may be accurately controlled, and skillful timing of the motions of the operatives as necessary in pouring and wiping is obviated. The time and skilled labor required for properly "beating in" and fitting the sleeve ends and parts, for wiped joints are obviated, as are also the uncertainties and defects of such method.

While we are aware that attempts have heretofore been made to seal cable joints by the use of molds for casting solder for the purpose, these attempts so far as we are aware did not obviate the necessity of "beating in" and specially fitting the ends of the joint sleeve. Neither were the molds of such form that the solder could be introduced in divided solid state and then be heated under controlled conditions to overcome the numerous difficulties of the "wiping" method.

In practising this invention the solder composition used may be selected without adhering to the requirements for obtaining a plastic mixture. Yet the resulting cast walls of solder are substantially homogeneous throughout, and the porosity encountered in hand formed wipes is eliminated. The solder mixture remains essentially constant as it is retained in the casting cavity.

Since a definite plastic range is not required of the solder for this method, it is possible if desired to choose a solder mixture close to the eutectic, thereby requiring less heat for melting, with less chance of injury to the cable insulation.

Referring now to further features of the mold constructions, Figs. 17 to 20 inclusive comprise enlarged views of a mold such as Fig. 4. A desirable distribution of the cavities 77 for the cartridge heaters is here shown in further detail. It will be noted that several of the cavities as at 77' are located in the walls adjacent the pouring gate 79. The heaters in these cavities may usually be the last ones to be cut out of circuit, in order to keep the solder in the gate molten until the last. Thereby sufficient solder may be introduced to compensate for all of the shrinkage before the gate is solidified. The abutting faces of the mold sections should be accurately finished to insure a close fit and the surfaces may be fixed against sliding with respect to each other during application of the mold as by pins 83. In order that the mold sections may be good conductors of heat, while being light in weight for convenient use, they are preferably formed of cast aluminum or aluminum alloy. Aluminum alloy known as "No. 43" in the trade has proven satisfactory. The mold surfaces which are to be in contact with the solder should be suitably treated as by a so-called "anodizing" process to prevent the solder from adhering thereto. Fig. 19 indicates the manner in which the cartridge heaters as at 84 of well-known construction may be inserted into the cavities 77. As shown in Fig. 17, each of the manual clamping elements may comprise for example a threaded stud as at 85, fixed in one of the mold sections and adapted to be engaged by an internally threaded piece as at 86 which is fixed to a finger piece 87 but is rotatably mounted within a lug on the mold section. This arrangement avoids the use of any loose pieces separate from the mold sections, so that the use of the molds is confined under-

ground work for example is facilitated without danger of loss of parts.

In Figs. 9 to 13 inclusive, an alternative form of mold is shown with electrical heating means permanently embodied within the mold sections. The heating means here may comprise resistance elements permanently embedded with refractory insulation in metallic tubes as at 88, 89 and of a type well known per se. These elements may be bent into arcuate form as shown in Fig. 10 and then cast within the mold sections along the region intermediate between the intended location of the cable sheaths and the joint sleeve. Suitable connections for these resistance elements are shown in Fig. 14. It will be noted that the ends of each element may be brought out to quick-detachable electrical terminals as at 90 to 97 inclusive, thus facilitating disconnecting the heating current from one of the mold portions while the remainder is still heated for reasons above explained. As shown in Fig. 14, an electrical thermostat 98 of a suitable well-known construction may be placed in series with the circuit of the heating elements and shunted by a condenser 99 to prevent arcing at the thermostat. The thermostat and condenser may be mounted within suitable cavities therefor in one of the mold sections so as to form a semi-permanent part thereof as shown in Figs. 10 and 11. A suitable closure as at 100 may be provided along one of the mold sections for housing the connections between the thermostat and the terminals 96, 97.

In Figs. 21, 22 and 23 an alternative form of mold construction is shown, which is adapted to be applied to a group of three symmetrically located cables. Parts and features of these figures corresponding to those of Fig. 17 are identified by the same reference numerals accompanied by prime marks and accordingly the construction, purposes and uses of this embodiment will be apparent from the above explanations. The external appearance of the finished solder seal formed with the mold of these figures is illustrated in perspective in Fig. 24.

While the invention has been described in detail with respect to particular preferred examples, it will be understood by those skilled in the art after understanding the invention that various changes and modifications may be made without departing from the spirit and scope of the invention, and it is intended therefore in the appended claims to cover all such changes and modifications.

Various features of the molding means herein disclosed are claimed in applicants' copending application Ser. No. 379,016, filed February 15, 1941.

What is claimed as new and desired to be secured by Letters Patent is:

1. The method of sealing an insulated electric cable having a metallic sheath, in respect to a metallic sleeve into the end of which the cable extends, which comprises placing barrier means around the cable, between the cable and sleeve near an end of the latter to form an enclosure, introducing a quantity of solder in solid state and in such divided form that it may be poured into said enclosure, and applying sufficient heat to said enclosure to melt said solder, whereby the resulting body of solder when cooled integrally seals the cable sheath in respect to the sleeve.

2. The method of sealing an insulated electric cable having a metallic sheath, in respect to a

metallic sleeve into the end of which the cable extends, which comprises placing barrier means around the cable, between the cable and sleeve, near an end of the latter to form an enclosure, introducing a quantity of solder in solid state and in such divided form that it may be poured into said enclosure, and applying heat from a source within the barrier means to melt said solder, whereby the resulting body of solder when cooled integrally seals the cable sheath in respect to 10 the sleeve.

3. The method of sealing an insulated electric cable having a metallic sheath, in respect to a metallic member receiving same, which comprises placing a mass of solder pellets around the cable sheath at the location of the desired seal, and melting said pellets whereby the resulting body of solder when cooled integrally seals the cable sheath in respect to said member.

4. The method of sealing an insulated electric cable having a metallic sheath, in respect to a metallic sleeve receiving the cable, which comprises providing a pair of spaced barriers forming a cavity therebetween and between the walls of the sleeve and the cable, filling said cavity 25 with solder shot, and melting said shot whereby the resulting body of solder when cooled integrally seals the cable sheath in respect to said sleeve.

5. Means for sealing a metal-sheathed electrical cable within the end of a surrounding metal sleeve of larger diameter for enclosing a cable joint, said means affording rigid mutual support between the cable and sleeve end and comprising a disc-like wall of solder substantially flush at its outer surface, with the end of the sleeve and cast in situ into integral sealing relationship with the sheath and sleeve, the cable also being encircled by and sealed to a flange of solder integral with said disc-like wall and extending outwardly therefrom along the cable sheath.

6. In a joint construction for metal sheathed electrical cables, a sleeve surrounding the cable sheath in spaced relation thereto, means integrally sealing the edges at the end of the sleeve in respect to the cable sheath and affording rigid mutual support between the sheath and sleeve, comprising a disc-like wall of solder cast in situ, the cable also being encircled by and sealed to a flange of solder integral with said wall and extending outwardly therefrom along the cable sheath, and a sprue extending radially from said flange along the outside surface of said wall to a point just outside the sleeve edge.

7. Barrier means adapted to close the space between a cable sheath and a cable joint sleeve, against passage of molten solder inwardly of the joint, comprising a disc-like metallic member

said member being formed at its periphery with a wide flange for extending along and in contact with the inside walls of the sleeve for a sufficient distance inwardly of the joint so that molten solder passing between said flange and said walls 5 may become cooled and solidify before escaping into the joint.

8. Barrier means adapted to close the space between a cable sheath and a cable joint sleeve, against passage of molten solder inwardly of the joint, comprising a disc-like metallic member, said member being apertured for passage of the cable therethrough, the aperture being formed with a generally conical flange, the constricted 15 portion of such flange being adapted to closely embrace the cable sheath.

9. Barrier means adapted to close the space between a cable sheath and a cable joint sleeve, against passage of molten solder inwardly of the joint, comprising a disc-like metallic member, said member being apertured for passage of the cable therethrough, the walls of the aperture being generally conical and extending for a substantial distance inwardly of the joint to a constricted portion for closely embracing the cable and adapted to receive packing means.

10. The method of sealing an insulated electric cable having a lead sheath, in respect to a lead sleeve encircling the cable in spaced relation thereto, which comprises inserting into the sleeve near the end thereof a permanent barrier for closing off the space between the cable and sheath, temporarily applying molding means embracing the cable and fitting the end of the sleeve 30 to form an enclosed cavity within the sleeve and between the barrier and molding means, heating said molding means from a source therein to a controlled temperature of molten solder and lower than the melting temperature of the sheath and sleeve, while introducing a mass of solder, including lead, filling said cavity, then discontinuing such heating, whereby said solder is cast 35 integrally with the sheath and sleeve, and finally removing said molding means.

11. The method of applying a mass of solder in bonded relationship to a lead sheath of an insulated electric cable, which comprises temporarily securing to the sheath a mold having at the surface of the sheath a cavity shaped in accordance with the desired mass, introducing solder flux into said cavity, pouring a mass of solder pellets into said cavity, and melting said pellets by heating said mold, whereby the resulting body of solder when cooled forms a mass integral with the lead sheath.
